United States Patent Office

Des. 220,727
Patented May 11, 1971

220,727

AIRCRAFT

Ralph V. Sawyer, 45432 Leatherwood,
Lancaster, Calif. 93534

Filed Jan. 5, 1970, Ser. No. 20,767

Term of patent 14 years

Int. Cl. D12—07

U.S. Cl. D71—1

Fig. 1

Fig. 2

Fig. 3

Fig. 4

Fig. 5

FIG. 1 is a perspective view as seen from the upper left front quarter of the aircraft of my invention;

FIG. 2 is a front elevational view of said aircraft;

FIG. 3 is a rear elevational view of said aircraft;

FIG. 4 is a left side elevational view of said aircraft; and

FIG. 5 is a plan view of the aircraft of my invention.

The right side view of the aircraft of my invention is a mirror image of the left-hand side as shown in FIG. 4.

I claim:

The ornamental design for an aircraft, as shown and described.
